UNITED STATES PATENT OFFICE.

JOHN T. SMITH, OF NORWAY, IOWA.

CLOTHES-LINE TIGHTENER.

SPECIFICATION forming part of Letters Patent No. 607,892, dated July 26, 1898.

Application filed February 19, 1897. Serial No. 624,098. (No model.)

To all whom it may concern:

Be it known that I, JOHN T. SMITH, a citizen of the United States, residing at Norway, in the county of Benton and State of Iowa, have invented certain new and useful Improvements in Clothes-Line Tighteners; and I do hereby declare the following to be a full, clear, and exact description of the invention, such as will enable others skilled in the art to which it appertains to make and use the same.

This invention relates to improvements in clothes-line fasteners; and the object of the same is to provide a combined clothes-line fastener and tightener, in which the slack of the clothes-line may be taken up by simply pulling upon one end of the same, the releasing of the clothes-line after the slack is taken up effecting the securing of the same in its adjusted position.

The invention consists in the novel features of construction hereinafter fully described, claimed, and illustrated by the accompanying drawings, in which—

Figure 1 is a perspective view of my device. Fig. 2 is a side elevation of the same in position for adjusting the clothes-line for removing the slack in the same, and Fig. 3 is a similar view showing the position of the parts after the clothes-line has been released and secured in its adjusted position.

Referring to the accompanying drawings, 1 indicates the post or support, to which the attachment is secured by means of the bolt 2, which passes through the horizontal arm 3 thereof and is secured by the nut 4. This nut 4 is provided with the operating-handle 5, whereby the same may be operated without the use of a wrench, and it also serves to form a reel upon which the end of the rope may be wound.

The arm 3 has its upper edge cut downward, as shown, to form the inclined or wedge-shaped surface 6, which terminates at its inner end in the straight portion 7. The arm 3 is provided with the straight wall 8, which forms a shoulder or stop against which the rear end of the wedge-shaped block 9 is adapted to abut. This wedge-shaped block 9 has pivoted to either side of the same the straps or bars 10. These bars are pivoted at their lower ends to the opposite sides of the arm 3 by bolts 11,

which pass through the said arm. Thus it will be understood that the wedge-shaped block is adapted to swing on the straps or bars 55 to which it is pivoted and its inclined surface 6 coact with the inclined surface 6 of the arm 3.

The clothes-line 12 is passed through the perforation 13 in the forward end of the arm 3 and through the perforation 13' in the top 60 wall of the block 9, where it passes under the inclined surface of the said block and through the perforation 14 at the rear wall of the same. From this point the rope passes downward through the perforation 15 in the straight surface 7 of the arm and is coiled about the reel. The portion of the rope beneath the wedge-shaped block rests in the groove 16 provided therefor.

When it is desired to take up the slack in 70 the clothes-line, the free end of the same is drawn upon (the opposite end of the clothes-line having been secured to a supporting object) and the wedge-shaped block is drawn backward, releasing the rope and permitting 75 the slack to be taken out of the clothes-line. The instant the end of the clothes-line is released the tension of the line will draw the wedge-shaped block forward upon the inclined surface 6 upon the arm 3 and wedge the rope 80 between the two inclines. The groove in the bottom of the block 9 is not deep enough to entirely receive the rope, so that enough of the same projects therefrom to enable a wedging action to be effected.

From the above description of my invention it will be understood that the greater the strain upon the line by the garments thereupon the tighter the rope will be secured and its slipping prevented.

It will be noted that I have produced a very simple clothes-line fastener which firmly clamps the clothes-line, the operation of the same being accomplished by simply releasing the end of the line after the slack has been 95 taken out of the same.

Having thus described my invention, what I claim as new, and desire to secure by Letters Patent, is—

1. A clothes-line fastener comprising a support, a horizontal arm secured to the support by a bolt, a securing-nut upon the end of the bolt, an operating-handle upon the nut for moving the same, said operating-handle con-

stituting a reel upon which the free end of the rope can be wound, an inclined surface upon the arm, an inclined block pivoted to the arm, and a rope secured at one end to a 5 supporting object, its opposite end passing through the arm and wedge, extending beneath the inclined surface of the wedge and outward to the rear wall of the same and thence downward through the arm, the parts 10 operating substantially as set forth.

2. A clothes-line fastener comprising a support, a horizontal arm secured thereto, the upper edge of said horizontal arm formed with an inclined surface, a block having its under 15 edge inclined, straps pivoted at their upper ends to each side of the block and at their lower ends to the horizontal arm, and a clothes-

line attached at one end to a securing object, its opposite end passing through a perforation in the forward end of the horizontal arm to the 20 top of the block downward to its inclined surface and passing along said surface, through a perforation in the rear wall of the block and thence downward through a perforation in the horizontal arm, the parts operating substantially as set forth. 25

In testimony whereof I have signed this specification in the presence of two subscribing witnesses.

JOHN T. SMITH.
